UNITED STATES PATENT OFFICE.

JAMES S. NICHOLS, OF ATLANTA, GEORGIA.

STEAM-SUPERHEATER.

1,275,080.

Specification of Letters Patent. Patented Aug. 6, 1918.

Application filed May 8, 1915. Serial No. 26,873.

To all whom it may concern:

Be it known that I, JAMES S. NICHOLS, a citizen of the United States, residing at Atlanta, in the county of Fulton and State 5 of Georgia, have invented new and useful Improvements in Steam-Superheaters, of which the following is a specification.

The present invention relates to improvements in superheaters for steam boilers in 10 general, and it is particularly applicable to steam locomotives.

The primary objects of the invention are to provide an improved superheater which will not only realize the benefits and advantages derived from the superheaters as heretofore or at present used, but which will obviate the disadvantages found to exist, and which will operate with greater efficiency, a circulation of steam being maintained in the tubes of the superheater continuously, thus providing for a constant supply of superheated steam which is ready for immediate use, avoiding the development of excess of pressure of superheated steam or 25 the waste of steam or water, or overheating or burning out of the superheater; to provide an improved valve construction and arrangement whereby control of the engine will be certain and positive and the supply 30 of superheated steam to the engine for motive power and the supply of saturated steam thereto for starting, stopping or lubricating purposes may be effected, and to provide improvements in the construction of the super- 35 heater whereby the superheating of the steam is accomplished with greater efficiency and the superheater elements are protected from burning or other injury.

To these and other ends the invention consists in certain improvements and combinations and arrangements of parts all as will be more fully described, the features of novelty being pointed out particularly in the claims at the end of the specification.

45 In the accompanying drawing:

Figure 1 represents a central longitudinal section taken vertically through the forward portion of a steam boiler equipped with a superheater constructed in accordance 50 with the present invention.

Fig. 2 is a top plan view of the controlling valve and its casing, the top of the casing being removed.

Fig. 3 represents a longitudinal section of 55 one of the tubes of the boiler and one of the superheater elements fitted therein.

Fig. 4 represents a section on the line 4—4 of Fig. 3.

Figs. 5 and 6 represent transverse sections on the lines 5—5 and 6—6, respectively, of 60 Fig. 3.

Fig. 7 represents a central vertical section through the controlling valve and its casing.

Figs. 8, 9 and 10 represent transverse sections through the controlling valve, showing 65 the same in three different positions.

Similar parts are designated by the same reference characters in the several views.

The present invention is applicable generally to steam boilers of various types, 70 where it is desirable or necessary to secure advantages from the use of superheated steam. The embodiment of the invention which is shown in the accompanying drawing and will be hereinafter described in detail is especially adapted to fulfil the conditions incident to the installation of superheaters on steam locomotives, although it is to be understood that the invention is not confined to this particular use nor to the 75 80 particular construction shown, as other uses and equivalent constructions are contemplated.

In the present instance, Fig. 1 represents, for instance, a tubular steam boiler of the 85 locomotive type, 1 designating the shell having a steam dome 2, a fire box 3, a smoke box 4, forward and rear tube sheets 5 and 6, respectively, and tubes 7 extending through the water space of the boiler between the fire box and smoke box and connecting the forward and rear tube sheets, it being understood that in this type of 90 boiler the heated gases or products of combustion flow longitudinally through these 95 tubes in passing from the fire box to the smoke box.

A suitable number of boiler tubes contain superheater elements, Figs. 3 to 6, inclusive, showing one of these superheater 100 elements in detail. As appears in these figures, each superheater element comprises a tube or pipe having an inlet end 8 and an outlet 9. Each superheater element is preferably constructed as follows: The tube 105 or pipe comprising the superheater proceeds from the inlet end 8 thereof rearwardly to a point about midway of the length of the superheater element, where it is formed with a return bend 10, and the tube or pipe then 110 doubles upon itself, extending forwardly to the forward end of the superheater element.

where it is formed with a return bend 11. The tube or pipe is then extended rearwardly for substantially the length of the superheater element and is formed at the rear 5 with a return bend 12, the tube or pipe then extending forwardly to a point in proximity to the return bend 10 near the middle of the superheater element, at which point it is formed with a return bend 13 which is adjacent or opposite to the return bend 10. From the return bend 13 the pipe or tube extends rearwardly, where it is formed with a return bend 14 which lies directly above the return bend 12, and from the return 10 bend 14 the tube or pipe extends forwardly to the outlet terminal 9. In order to protect the return bends of the superheater element from the direct action of the flame or the highly heated gases, as well as the wearing effect of cinders, and to enable the superheater element to be extended to a point closer to the fire box than it has heretofore been deemed possible or expedient, a water jacket is provided for the return bends 12 15 and 14. This water jacket as shown comprises a tube 15 which preferably has a diameter about one-half the diameter of the boiler tube 7 and extends transversely through the boiler tube, the ends of the 20 transverse or water jacket tube 15 being fitted tightly in the walls of the boiler tube 7 and providing a chamber or passageway for the water in the boiler. The forward side of the transverse tube 15 is formed with 25 indentations 16 in which rest the return bends 12 and 14 of the superheater element, the tube 15 performing the function of protecting the return bends of the superheater from the direct action of the flames or 30 highly-heated gases and from the cinders passing through the boiler flue, and the indentations in this transverse tube serve to support or hold the superheater in proper position, within the flue. Means is also 35 provided for protecting the intermediate return bends 10 and 13 from the direct influence of the flame or highly-heated gases and cinders. As shown, a block 17 is provided which has recesses 18 and 19 formed 40 in its front and rear sides into which the return bends 10 and 13 are fitted, these return bends being thereby inclosed and protected from the influences referred to above. 45 The superheater element of the construction just described not only avoids the destructive influences referred to above, but it enables the superheater to be placed closer to the fire box and to be made in greater length than heretofore, and moreover, the number 50 of return bends which it possesses insures greater efficiency in the breaking up of the wet core in the saturated steam, with the result that the superheating action is more uniform and complete.

60 The inlet ends 8 of the superheater ele-

ments communicate with the saturated steam chamber or box 20, and the outlet ends 9 of the superheater elements communicate with a superheated steam chamber or box 21. The present invention provides a novel valve 70 construction and arrangement whereby the superheated steam and the saturated steam are controlled, providing always for a continuous circulation of steam through the superheater elements. In the embodiment of 75 the invention shown, a valve casing 22 is provided which is advantageously located in the closest proximity to the engine or cylinders of a locomotive in order to reduce to a minimum the length of the piping and consequently the volume of steam between the valve and the engine or cylinders and which is beyond the control of the valve. In the present instance, the valve is located in the smoke box 4 and at the forward side of the 80 forward flue sheet 5. The valve casing is suitably divided or partitioned to form the saturated steam chamber 20, the superheated steam chamber 21, and the motive steam chamber 23, this latter chamber having its 85 outlet connected by the branch pipe 24 to the driving cylinders or engine. The valve casing is also formed with a valve housing 25, and in the present instance a single rotatable valve is fitted into the valve housing 90 to control both the saturated steam and the superheated steam. A valve 26 of this type is shown in the form of a rotary plug which is slightly conical or tapered, it having an enlarged diameter at the bottom, and it is 95 formed with ports 27, 28 and 29 for the control of superheated steam and with ports 30 and 31 for the control of saturated steam, these sets of ports being located in different planes longitudinally of the valve. The 100 valve housing 25 is formed with a port 33 leading from the superheated steam chamber 21; the port 34 communicates with a pipe 35 which pipe leads to the dome 2, and the housing 25 is also formed with a port 36 105 which leads into the motive steam chamber 23. The ports 33, 34 and 36 are arranged to coöperate with the ports 27, 28 and 29, respectively, of the valve. The valve housing 25 is also formed in a different plane with 110 ports 37 and 38 to coöperate with the ports 30 and 31, respectively, the port 37 communicating with the saturated steam chamber 20 and the port 38 with the motive steam chamber 23. The saturated steam chamber 115 20 is in communication with the steam dome 2 through a pipe 39 which leads from the upper portion of the steam dome to the saturated steam chamber 20. The present invention enables the usual throttle valve in 120 the steam dome to be dispensed with, a single valve serving as a throttle to control both saturated and superheated steam. To enable the valve 26 to be adjusted as desired to 125 supply saturated or superheated steam to the 130

engine or driving cylinders, it is provided with a stem 40 which preferably extends to the exterior of the boiler or smoke box and is provided with an arm or crank 41 which in turn may be connected by a rod 42 to a suitable lever or handle located in the cab of the locomotive at any point convenient for the engineer the exterior location of the operative connections for the valve avoiding 5 delays and other objections found to exist with the arrangements of the operative connections of the ordinary type of valve, which connections have heretofore been located within the steam space of the boiler, 10 and hence such connections were inaccessible for inspection or repair and also required stuffing boxes which are troublesome.

The operation of the boiler equipped with a superheater and controlling valve embodying the present invention may be briefly described as follows:—

Under normal conditions with the engine not in running operation or with the locomotive at a standstill, the valve 26 will occupy the position shown in Fig. 10, the superheated steam port 36 and the saturated steam port 38 leading to the motive steam chamber 23 being then closed and the ports 27 and 28 of the valve will establish communication between the ports 33 and 34 of the valve housing. Saturated steam will then flow from the steam dome through the pipe 39 into the saturated steam chamber 20 and will then flow through the superheater elements in the boiler tubes, this steam being superheated on its way through the superheater elements and the superheated steam from the superheater elements will enter the superheated steam chamber 21, and as this steam is not being used at this time it will return to the steam dome through the ports 33, 27, 28 and 34 and the pipe 35. This circulation of steam through the superheater elements will be set up and maintained thermally, the saturated steam descending to the superheater elements being heavier than the superheated steam which rises from the superheater elements. This circulation of steam through the superheater elements will increase the efficiency of the boiler owing to the utilization of the heating surface of the superheater elements to raise the temperature of the steam in the boiler, and it will avoid the development of excessive pressure in the superheater which heretofore required release and loss of steam power or water and overheating and burning of the superheater elements. In starting the engine, it is necessary, in order to obtain proper or the best results, to feed the saturated steam to the cylinder. This is accomplished by shifting the valve 26 into the position shown in Fig. 9, this movement of the valve bringing 15 the ports 30 and 31 therein into communication with the ports 37 and 38 of the valve housing and admitting saturated steam from the chamber 20 through the valve and into the motive steam chamber 23, this saturated steam then flowing to the cylinders 70 through the pipe 24. While the valve is in this position, the circulation of steam through the superheater elements continues, owing to communication being maintained between the ports 27 and 28 of the valve 75 with the ports 33 and 34 of the valve housing, the superheated steam, however, flowing from the superheater elements back to the steam dome. After the engine or locomotive has been started, it is desirable to 80 cut off the flow of saturated steam to the engine or cylinders and to supply the superheated steam thereto. This is accomplished by shifting the valve 26 into the position shown in Fig. 8, the ports 30 and 31 of the 85 valve being out of communication with the ports 37 and 38 of the valve housing, thus cutting off the supply of saturated steam from the engine or cylinders, and the ports 27 and 29 of the valve being in communication 90 with the ports 33 and 36 of the valve housing, superheated steam then flowing from the superheated steam chamber 21 through the ports 27 and 29 into the motive steam chamber 23, thence through the pipe 95 24 to the engine or cylinders. With the valve in this position, the return of superheated steam to the steam dome is cut off as the port 28 of the valve is then out of registry with the port 34. The throttling 100 of either the saturated or the superheated steam may be accomplished by uncovering more or less the ports in the valve. In stopping the engine or locomotive, it is expedient to use saturated steam, and this is 105 accomplished by rotating the valve back to the position shown in Fig. 9, the supply of superheated steam to the engine or cylinders being thereby cut off and saturated steam being supplied to the engine or cylinders. 110 Furthermore, the valve may be adjusted or set to feed saturated steam to the cylinders, from time to time, in order that the saturated steam may serve the purpose of lubricating the cylinders and pistons and other 115 working parts. Owing to the proximity of the throttle or controlling valve to the cylinders, the train, when the invention is applied to a locomotive, may be stopped promptly by the air brakes, as the amount 120 of steam beyond the throttle or controlling valve is reduced to a minimum as compared with the previously used superheater systems where a considerable amount of steam must be worked out of the piping beyond 125 the controlling valve before the driving of the locomotive ceases.

According to the present invention, the steam supply pipe 39 leads from the top of the dome, and consequently it takes up the 130

best part of the saturated steam, mixed with superheated steam which has been returned to the dome by the pipe 35, this steam passing either into the superheater elements and 5 being used for power as superheated steam, or this superheated steam is returned to the steam dome for subsequent use, thereby avoiding waste or loss of water which is a fault in systems as heretofore used, and 10 furthermore, a constant circulation or flow of steam through the superheater elements protects these elements at all times from overheating or burning. And, moreover, a supply of superheated steam is constantly 15 on hand ready for immediate use, whereas in systems as heretofore used, with the throttle valve located in the steam dome, considerable delay ensued in obtaining superheated steam, depending upon the flow 20 of the saturated steam from the dome and then through the superheater before the same was ready for use. The construction of the superheater elements is such that their superheating action will be more efficient 25 and they will be protected from flame or highly heated gases and from cinders. Furthermore, the arrangement of the superheating units or elements is such that draft controlling dampers or other devices of a 30 similar nature are unnecessary, this advantage arising from the fact that a constant circulation of steam is maintained through the superheater and the superheater elements or units are protected from injury or 35 damage. Furthermore, the construction and arrangement of the throttle or controlling valve is such that there is no danger of the accumulation of steam pressure between the throttle or controlling valve and the engine or cylinders which in previously used 40 systems has resulted in the starting of the locomotive, while the throttle or controlling valve is closed.

What I claim is:

1. The combination with a steam boiler, of a superheater, and a single manually controlled valve operative when in one position to return superheated steam from the superheater to the boiler and operative in another 50 position to direct saturated steam from the boiler to an outlet for use while superheated steam is returned to the boiler, and operative in a third position to interrupt the return of superheated steam from the superheater to the boiler and to discharge such superheated steam to the outlet for use.

2. The combination with a steam boiler, of a superheater, and a manually controlled valve having ports capable of causing circulation of steam from the superheater outlet to the boiler, said ports being also capable of interrupting such circulation and discharging superheated steam from the superheater to an outlet for use, the valve 65 also having ports capable of discharging

superheated steam from the boiler to said outlet when the valve is in a position to establish circulation between the superheater outlet and the boiler.

3. The combination with a steam boiler, 70 of a superheater, and a valve normally operative to cause circulation of steam from the superheater outlet to the boiler and operative sequentially when moved in one direction to discharge saturated steam direct 75 from the boiler to an outlet for use while the circulation of superheated steam from the superheater outlet to the boiler is maintained, and thence to interrupt such circulation of superheated steam to the boiler and 80 direct such superheated steam to the outlet.

4. The combination with a steam boiler, of a superheater, and a combined throttle and control valve capable of establishing circulation of superheated steam from the 85 superheater outlet to the boiler when in one position, capable of interrupting such circulation and directing and throttling the flow of superheated steam from the superheater to an outlet for use when in another 90 position, and capable of directing and throttling the flow of saturated steam direct from the boiler to said outlet when in another position and while said circulation between the superheater outlet and the 95 boiler is maintained.

5. The combination with a steam boiler, of a superheater, a saturated steam chamber, superheated steam and motive steam chambers, the saturated steam chamber being 100 connected to the steam space of the boiler and to the inlet of the superheater, and the superheated steam chamber being connected to the superheater outlet, and a valve having ports operative to return superheated 105 steam from the superheater to the boiler in one position of the valve and to direct superheated steam from the superheated steam chamber to the motive steam chamber in another position of the valve, the valve also having saturated steam ports operative to connect the saturated steam chamber to the motive steam chamber.

6. The combination with a steam boiler, of a superheater, a saturated steam outlet 115 pipe leading from the boiler, a superheated steam pipe leading into the boiler, the superheater being connected to receive steam from said saturated steam outlet pipe, and a valve capable of establishing communication between the outlet of the superheater and said superheated steam pipe leading into the boiler and also between the outlet of the superheater and an outlet for use, said valve being also capable of controlling the flow 120 of saturated steam from said saturated steam pipe direct to said outlet.

7. A superheater unit for steam boilers comprising a pipe having return bends at opposite ends of the superheater unit and 125

- also having opposed return bends formed intermediately the ends of the unit, and means connecting and incasing said opposed intermediate return bends.
- 5 8. A superheater unit for steam boilers comprising a pipe having opposed return bends formed intermediately the ends of the unit, and means for connecting and protecting said bends from the influence of 10 flame or heat and cinders.
9. A superheater unit for steam boilers comprising a pipe having opposed return bends formed intermediately the ends of the unit, and a member recessed to receive and 15 protect said opposed return bends.
10. The combination of a boiler tube, a superheater unit therein, and a water jacket in the tube for protecting one end of said unit.
- 20 11. The combination of a boiler tube, a superheater unit therein having return

bends at its rear end, and a water jacket for protecting said return bends.

12. The combination of a boiler tube, a superheater unit therein having return 25 bends at its rear end, and a tube extending transversely of said boiler tube adjacent to said return bends of the superheater unit.

13. The combination of a boiler tube, a superheater unit therein having return 30 bends at its rear end and a tube extending transversely of the boiler tube and having indentations in its forward side to receive and protect said return bends at the rear end of the superheater unit.

35

In testimony whereof I have hereunto set my hand in presence of two subscribing witnesses.
